US00D683309S

(12) **United States Design Patent**
Chiu et al.

(10) **Patent No.:** US D683,309 S
(45) **Date of Patent:** ** May 28, 2013

(54) **ELECTROMAGNETIC RECHARGE DEVICE**

(75) Inventors: **Hung Tzu Chiu**, Miaoli County (TW);
Yu Chiehmr Ho, Hsin-Chu (TW)

(73) Assignee: **Waltop International Corporation**,
Hsinchu (TW)

(**) Term: **14 Years**

(21) Appl. No.: **29/424,513**

(22) Filed: **Jun. 13, 2012**

(30) **Foreign Application Priority Data**

Dec. 20, 2011 (TW) ..... 100306993 A

(51) **LOC (9) Cl.** **13-02**

(52) **U.S. Cl.**

USPC **D13/108**

(58) **Field of Classification Search**

USPC .. D13/107-110, 118-119, 184, 199; D19/35,
D19/41, 45, 51; 320/107-115

(57) **CLAIM**

The ornamental design for a electromagnetic recharge device, as shown and described.

DESCRIPTION

FIG. 1 is a perspective view of a design for a electromagnetic recharge device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
